COMBINATION CLOSURE CAP AND DISPENSER

George H. Sinclair, Richmond Heights, and Wayne H. Rush, St. Louis, Mo.

Application March 6, 1957, Serial No. 45,128

Term of patent 14 years

(Cl. D58—26)

Fig. 1 is a side elevational view of a combination closure cap and dispenser embodying our new design,

Fig. 2 is a top plan view thereof,

Fig. 3 is a front elevational view showing the dispensing end of the cap, and

Fig. 4 is a rear elevational view showing the end opposite to the dispensing end of the cap.

We claim:
The ornamental design for a combination closure cap and dispenser, substantially as shown.
